UNITED STATES PATENT OFFICE.

ALEXANDER BOYNTON, OF SAN ANTONIO, TEXAS.

POLISHED ROD ROTOR.

Application filed June 29, 1926. Serial No. 119,507.

This invention relates to polished rod rotors especially adapted for use in connection with pumping wells.

The invention forming the subject matter 5 of this application contemplates the provision of economical and reliable means for intermittently rotating the polished rod and the reciprocating mechanism connected thereto to exert an intermittent tightening 10 effect on the rods at the joints thereof and to avoid the formation of squirt grooves in the working barrel and the cups or plunger, as the case may be, which squirt grooves seriously cut down production and emulsify the 15 oil.

A further and equally important object is to provide a polished rod rotor embodying novel means by which twisting of the rods to the breaking point as a result of sticking of 20 the cups or plunger is prevented, this feature of the invention being adapted to render the rotor temporarily inoperative when the back strain in the rods as a result of the sticking of the cups or plunger exceeds a predetermined 25 point.

Another aim is to provide a rotor which may be quickly applied to the beam of a pumping jack without the exercise of unusual skill and without substantially altering 30 the construction of the parts already in use, both of these features making the invention more acceptable to the trade.

Other objects and advantages will be apparent during the course of the following 35 description.

In the accompanying drawings forming a part of this application and in which like numerals are employed to designate like parts throughout the same:

40 Figure 1 is a perspective of the improved rotor applied;

Figure 2 is a detail sectional view through a portion of the motion transmitting mechanism;

45 Figure 3 is a vertical transverse sectional view taken on line 3—3 of Figure 2;

Figure 4 is a fragmentary front elevation of the rotor applied;

50 Figure 5 is a fragmentary side view of the rotor applied;

Figure 6 is a fragmentary front elevation illustrating a slight modification of the invention;

55 Figure 7 is a horizontal sectional view taken on line 7—7 of Figure 6.

In the drawings, the numeral 5 designates

the beam of an Oklahoma pumping jack, which beam is, as shown in Figure 1, formed principally from a pair of channel beams having their flanges directed outwardly. 60 Figure 1 further shows the invention is provided with a special trunnion 6 to receive the polished rod 7, the lateral branches of the trunnion being provided with grooved enlargements 8 at the ends thereof for engagement by the eyes of eye-bolts 9. The eye-bolts 9 are threaded into the upper terminal portions of the sides of a U-shaped stirrup 10 whereby the stirrup is suspended beneath the beam in such a manner that the centrally arranged opening in the bight portion thereof receives the polished rod. The threaded connection between the bolts 9 and the sides of the stirrup 10 permits adjustment of the stirrup with respect to the bolts 9 and other 70 parts of the rotor.

The stirrup 10 constitutes a support for a power transmitting unit or member in the nature of a beveled gear 12, the hub 14 of which is extended a substantial distance below the gear and seats in a rather shallow recess 15 in the bight portion of the stirrup. Suitable fastening devices such as set screws 16 may be employed to firmly lock the hub 14 to the polished rod so that when the hub 14 is turned by a means to be described the polished rod will also be turned. The recess 15 is adapted to receive a suitable lubricant to reduce friction between the lower end of the hub and the adjacent portion of 80 the stirrup to a minimum.

One of the most important features of the invention resides in the particular connection between the hub of the beveled gear 12 and the bottom wall of the recess 15 since these two parts constitute what might be said to be a frictional holding means contributing largely to the success of the invention. First it is pointed out that the load of the polished rod, the sucker rod, the cups or plunger, as the case may be, is transmitted from the polished rod clamp 20 of conventional design to the hub 14 and from the hub 14 to the stirrup. It is believed to be obvious that the load borne by the stirrup is transmitted to the special trunnion 6 and from the trunnion 6 to the beam. Now, during the normal operation of the rotor, during which period the cups or plunger, as the case may be, are free to turn under the influence of the rotor and the friction between the lower end of the hub 14 and the bottom wall of the recess will be 90 95 100 105 110

overcome easily and the hub will remain in the turned position.

However, should the cups or plunger stick in the working barrel a back strain will be built up in the sucker rods and when the actuating mechanism for the rotor is on its return stroke preparatory to again turning the rotor in a clockwise direction the back twist in the rods will cause the hub 14 to turn in a counter-clockwise direction. In other words, when the back strain in the rods exceeds a predetermined point or in fact approaches the breaking point, it will be sufficient to overcome the friction between the hub 14 and the stirrup as a result of the weight of the sucker rods, etc., and will cause the hub to move in a counter-clockwise direction since there is nothing of consequence to resist this movement.

Attention is now invited to Figures 2 and 4 which illustrate that the beveled gear 12 is in constant mesh with the pinion 24 formed on one end of or attached to a hollow shaft 26. The hollow shaft 26 is shown in these Figures as being provided with an annular series of ratchet teeth 27 adapted to be engaged by the ratchet teeth of a motion transmitting ratchet and sprocket wheel or element 28. The wheel 28 is rotatably mounted on the shaft 26 and the ratchet teeth of the same are urged into engagement with the ratchet teeth 27 by a coil spring 29. The coil spring 29 which is mounted on the shaft 26 is confined between the hub of the wheel 28 and the attaching portion 30 of a protecting shell 31. Figure 2 clearly illustrates that the shell 31 is threaded on the shaft 26, thereby making it possible to vary the tension of the spring 29. When the motion transmitting wheel 28 is turned in a counter-clockwise direction the ratchet teeth of the same will have driving engagement with the ratchet teeth 27 so that the shaft 26 and the beveled gear 24 at one end of the same are turned. However, when the combination wheel 28 is turned in a clockwise direction by a means to be described the ratchet teeth of the same will ride back on the ratchet teeth 27 so that no motion whatever will be imparted to the shaft 26 from this source. It is believed to be obvious that during the return of the combination wheel to a new driving position the spring 29 will be contracted. Each time the combination wheel rides over the ratchet teeth 27 the wheel 28 will be moved back to a position partly within the shell 31 so that if any ice or the like should happen to accumulate between the combination wheel and the shell it will be scraped off during the backing up and lateral movement of the combination wheel. Figure 2 shows this to be true.

Further reference to Figure 2 will clearly show that the shaft 26 is hollow for the reception of a lubricant which may be sup-

plied by way of the elbow 32, a lubricator cup or any other means found convenient, this feature forming no special part of the invention, but being valuable as a mechanical expedient. Suitable passages may be provided for the movement of the lubricant from the interior of the shaft to the areas to be lubricated.

Referring now to Figure 4 it will be seen that the shaft is confined between the upper and lower sections of a more or less U-shaped yoke 35, the sections of the yoke being provided at their meeting portions with lateral ears which may be connected by cap screws 36 or other suitable fastening devices. The meeting portions of the sections of the yoke may be formed with semi-circular recesses which cooperate in the formation of bearings for the terminals of the shaft 26, as clearly illustrated in Figure 2. The bearings for the reception of the terminals of the shaft 26 may be lined with an anti-friction metal or they may be merely machined, depending on the mechanical perfection desired and the use or abuse to which the device might be subjected.

Figure 5 clearly illustrates that the yoke 35 is received in a slot 37 in one of the vertical sides of the stirrup 10 so that the yoke is braced and held against movement. This figure also illustrates that the shell 31 is received in the enlarged intermediate portion of the slot 37 so that lost motion of the shaft 26 and the pinion 24 is avoided. The inner portions of the sections of the yoke 35 are provided with bearings 40 which receive the reduced terminals of the hub 14. Of course, it is necessary to place the hub 14 between the bearings 40 preparatory to the connection of the sections of the yoke 35; otherwise the hub 14 could not be connected to the yoke.

The sprocket teeth of the combination wheel are engaged by the intermediate portion of a sprocket chain 41, the ends of which are trained about adjustable sprocket wheels 42. Suitable guards 43, preferably of segmental formation, are extended about a portion of the chain at the sprocket wheels 42 and are mounted upon the same attaching bolts 44 as are the sprocket wheels 42. Figure 5 clearly illustrates that the attaching bolts 44 are extended through the slots 47 in an attaching arm 48. The attaching arm is in turn connected to the beam by a bracket 50.

It is believed to be obvious from an inspection of Figure 5 that the arm 48 extends on opposite sides of the plane of the polished rod so that when the beam is rocked the sprocket chain 41 will impart a rocking motion to the combination wheel 28 to bring about the intermittent turning of the polished rod, the sucker rods, and the cups or plunger, as the case may be. It is im-

portant to observe that the extent to which the combination wheel 28 is rocked may be controlled by an adjustment of the sprocket wheel attaching bolts 44 in the slots 47. 5 Of course, when the sprocket wheels 42 have been properly adjusted to bring about the desired rocking of the combination wheel 28, the bolts 44 are securely tightened so that the sprocket wheels 42 will be positively held against turning or bodily movement. 10 Slack in the chain 41 may be taken up by turning one or both of the sprocket wheels 42 in the proper direction and then tightening the same.

15 With reference to the foregoing description it will be seen that rocking of the beam on the down stroke will result in the turning of the combination wheel in a counter-clockwise direction, which turning of the combination wheel will result in the turning of the beveled gear 12 and consequently the polished rod, the sucker rods, and the cups in a clockwise direction whereby the formation of squirt grooves or jets is avoided. 20 This also brings about an intermittent tightening effect on the rods at the joints thereof so that parting of the joints is overcome.

Particular attention is invited to the fact 30 that the intermittent turning of the rods is accomplished on the down strokes of the movable equipment, during which strokes the weight of the column of fluid is not upon the rods, but, as is well known in the art, 35 is upon the standing valve or valves. On the up stroke of the rods the friction is substantially greater due to the weight of the column of fluid thereon and it is not near so easy to turn the rods.

40 In the form of invention illustrated in Figures 6 and 7, the bearings 40' of the sections of the yoke 35' are provided with apertured extensions or ears 60 arranged in line for the reception of a bolt 61 which 45 cooperates with the fastening devices 63 at the outer end of the yoke to hold the sections of the yoke together. It will be seen by reference to Figure 6 that the inner contact points 64 which cooperate in the formation 50 of the inner bearing for the shaft 26 are not connected by cap screws, or the like, but at this point a mere jam fit is employed.

Having thus described the invention, what is claimed is:

55 1. A polished rod rotor comprising an attaching member, a power transmitting unit mounted on the attaching member and having means whereby the same may be securely locked to a polished rod, a shaft having 60 means engaged with said power transmitting unit and having teeth, a motion transmitting wheel having teeth adapted to engage said first-named teeth, spring means urging the teeth of said motion transmitting 65 wheel into engagement with said first-named

teeth, and a driving member connected to said motion transmitting wheel.

2. A polished rod rotor comprising an attaching member, a power transmitting unit having means whereby the same may be 70 securely locked to a polished rod, a shaft having means engaged with said power transmitting unit and having ratchet teeth, a motion transmitting wheel having ratchet teeth adapted to engage said first-named 75 ratchet teeth, means urging the ratchet teeth of said motion transmitting wheel into engagement with said first-named ratchet teeth, a driving member connected to said combination wheel, and a yoke supporting 80 said shaft.

3. A polished rod rotor comprising a power transmitting unit having means whereby the same may be securely locked to a polished rod, a shaft having means engaged 85 with said power transmitting unit and having ratchet teeth, a power transmitting wheel having ratchet teeth, spring means urging the ratchet teeth of said power transmitting wheel into engagement with said first-named 90 ratchet teeth, and a yoke supporting said shaft and having means receiving the terminals of said power transmitting unit.

4. A polished rod rotor comprising an attaching member, a power transmitting unit mounted on the attaching member and having means whereby the same may be securely locked to a polished rod, a shaft having 100 means engaged with said power transmitting unit and having teeth, a motion transmitting wheel having teeth, spring means urging the teeth of said motion transmitting wheel into engagement with said first-named teeth, a driving member connected to said 105 motion transmitting wheel, and means whereby an end of said driving member may be anchored to the beam of a pumping jack.

5. A polished rod rotor comprising a power transmitting unit having means whereby the same may be attached to a polished rod, a shaft having constant connection with said power transmitting unit and being provided with ratchet teeth, a motion transmitting wheel rotatably mounted on said shaft and having ratchet teeth engaged with said first named ratchet teeth, a driving chain having connection intermediate the ends thereof with said motion transmitting wheel, and anchoring devices at the ends of said chain.

6. A polished rod rotor comprising a power transmitting unit having means whereby the same may be attached to a polished rod, a shaft having connection with said power transmitting unit and being provided with teeth, a motion transmitting wheel mounted on said shaft and having teeth engaged with said first-named teeth,

a spring urging said first and second-named ratchet teeth into constant engagement, a driving chain having connection with said combination wheel, anchoring devices at the ends of said chain, and an arm having means adjustably supporting said anchoring devices.

7. A polished rod rotor comprising a power transmitting unit having means whereby the same may be attached to a polished rod, a shaft having connection with said power transmitting unit and being provided with ratchet teeth, a motion transmitting wheel having ratchet teeth engaged with said first-named ratchet teeth, a driving chain having connection intermediate the ends thereof with said motion transmitting wheel, anchoring devices for said chain, an arm having means adjustably supporting said anchoring devices, and a yoke having bearings receiving said shaft.

8. A polished rod rotor comprising a power transmitting unit having means whereby the same may be attached to a polished rod, a shaft having connection with said power transmitting unit and being provided with teeth, a motion transmitting wheel rotatably mounted on said shaft and

having teeth, a spring urging said first and second-named teeth into engagement, a driving chain having connection with said motion transmitting wheel, anchoring devices for said chain, an arm supporting said anchoring devices, a yoke receiving said shaft, and a stirrup receiving a portion of said yoke to stabilize the same, said stirrup being provided with means whereby the same may be attached to a polished rod trunnion.

9. A polished rod rotor comprising a power transmitting unit having means whereby the same may be attached to a polished rod, a shaft having connection with said power transmitting unit and being provided with ratchet teeth, a motion transmitting wheel mounted on said shaft and having teeth engaged with said first-named teeth, a driving chain having connection intermediate the ends thereof with said motion transmitting wheel, a yoke having bearings receiving said shaft, and a stirrup receiving a portion of said yoke to stabilize the same, said yoke consisting of a plurality of sections having bearings rotatably receiving said power transmitting unit.

In testimony whereof I affix my signature.
ALEXANDER BOYNTON.
